UNITED STATES PATENT OFFICE.

ERNEST C. FASOLDT, OF ALBANY, NEW YORK, ASSIGNOR OF ONE-HALF TO
JOHN BOYD THACIER, OF SAME PLACE.

PRESSURE-REGULATOR.

SPECIFICATION forming part of Letters Patent No. 466,275, dated December 29, 1891.

Application filed December 26, 1890. Serial No. 375,853. (No model.)

To all whom it may concern:

Be it known that I, ERNEST C. FASOLDT, of the city and county of Albany, in the State of New York, have invented new and useful Improvements in Diaphragms for Pressure-Regulators, of which the following is a specification.

My invention relates to improvements in diaphragms for pressure-reducers and other similar apparatus; and the object of my invention is to provide a diaphragm which, while having strength to withstand an extreme degree of pressure, will possess elasticity sufficient to obtain a longer range of movement than is obtainable with an ordinary diaphragm capable of withstanding the same degree of pressure for which mine is designed. This object I attain by the mechanism illustrated in the accompanying drawings, which are herein referred to and form part of this specification, and in which—

Figure 1 is a vertical section taken at the central line of my diaphragm in its normal condition. Fig. 2 is a like section with the disks in their distended condition. Fig. 3 is a like section on a reduced scale, showing a modified form of the guard for the disks. Fig. 4 is a reduced plan view of another modification of the form of said guard. Fig. 5 is a side elevation of a pressure-reducer provided with my improved diaphragm, the lower part of the body of the reducer being shown in vertical section for the purpose of exposing the valve mechanism.

As represented in the drawings, A designates the cylindrical body of a pressure-reducer, the valve mechanism for the latter being omitted therefrom, as it forms no part of this invention.

B designates my improved diaphragm, which is secured to the body A by a cap C, which is preferably attached to said body by a screw-threaded neck D. Said diaphragm consists of two concentrically-corrugated metallic disks E, formed of resilient material and spaced apart by an annulus F to form a chamber G, into which steam or other fluid under pressure is admitted through an opening or openings 1, formed in the neck D. The disks E are made in the form of an annulus, and the central part of the lower disk

is secured to the upper end of the neck D by means of an annulus 2, which is secured to said neck by screws 3, so as to clamp the central part of said disk between the upper end of the neck D and the lower face of the annulus 2. The central part of the upper disk is clamped, in the manner just described, between the lower face of the hub H and the upper face of an annulus 4 by screws 5. An upper guard-plate I and a lower guard-plate J, of substantially the same form, are fitted to set over and form a guard for the corresponding disks E and to form the upper and lower faces of the diaphragm B. Said guard-plates are made dishing on the inner face to a degree that will conform to the limit of convexity required to be given to the disk by the pressure acting on their inner faces. As shown in Figs. 1 and 2, the concave face of each of said guard-plates is provided with concentric corrugations, which conform to and form bearings for the corrugations in the corresponding disks E; but, as shown in Fig. 3, the concave face of each of said guard-plates is made without corrugations, and in this modification the apex of each corrugation in the disks E will, when the disks are bulged out by pressure, bear upon the surface of the dished side of the guard-plates. The outer edge of the guard-plates I and J, disks E, and annulus F are secured by bolts 6, which pass through the several parts last named, and packings 7 are interposed between the contiguous faces of said disks and annulus to form a steam-tight joint at those points.

It will be seen that the entire weight of the diaphragm B rests upon the upper end of the neck D, the latter remaining in a stationary position during all changes of position of the other parts of the diaphragm. Preferably the lower disk is made thinner than the upper disk, so that said lower disk will more quickly yield to pressure than the upper one.

K designates an adjusting-screw which passes through the central aperture of the neck D and hub H and projects beyond the outer end of said hub. A nut L is fitted on said screw to bear upon the upper end of the hub H, and a packing 8 is interposed between said hub and nut for the purpose of forming a steam-tight joint at that point, so as to pre-

vent escape of steam or other fluid which may leak through the joint between the screw K and the bore of the aperture through the hub H. The lower extremity of the screw K is provided with a swivel-joint 9, to which a link 10 is pivoted, said link being a connection between the screw K and a valve mechanism consisting of an oscillating valve 11, which is fully shown and described in Letters Patent No. 449,071, granted to me March 24, 1891; but I do not limit myself to this form of valve, for the reason that my diaphragm can be used with equally satisfactory results with many other forms of valves. The adjusting-screw K is provided for the purpose of adjusting the movement of the pressure-reducing valve to the position that will obtain the required reduction of pressure in the steam or other fluid which passes through the apparatus, or, in other words, said adjusting-screw is designed to effect the setting of said valve in such manner that when the extreme fluid-pressure is prevented from entering into the apparatus said valve will be in the position required to have its closing movement produce the required degree of reduction of pressure in the apparatus.

My invention operates in the following manner: The pressure in the body of the pressure-reducer is admitted into the chamber G through the openings 1 in the stationary neck D, and in said chamber said pressure will act upon the inner face of each disk E. The effect of this pressure will be to force said disks to bulge outwardly into the forms shown in Fig. 2, whereby the lower guard-plate J will be raised into contact with the lower face of the lower disk E and the upper face of the upper disk E will be forced into contact with the lower face of the upper guard-plate I. Thereby the entire diaphragm B will be raised to a distance which corresponds to the concavity of the lower disk and the hub H will be moved in respect to the neck D to

a distance that equals the sum of the movements of both of said disks, the screw K acquiring an upward movement that is equal to that of the hub H. It will be seen that by this diaphragm, by reason of the disks E bulging in opposite directions, a much greater range of movement of the valve-moving mechanism can be obtained than with the single disk of an ordinary diaphragm.

What I claim as my invention, and desire to secure by Letters Patent, is—

1. In a diaphragm for pressure-regulators, the combination of two resilient metallic disks spaced apart by means of an annulus to form a chamber between them, one of said disks being centrally secured to a stationary neck provided with openings leading into said chamber and the other disk being centrally secured to a hub arranged to move from and toward said stationary neck, a pair of guard-plates secured to the outer face of said disks at their periphery, the inner face of each of said guard-plates having a dishing form corresponding to the disk and lying within the limit of the bulging movement of the disks, whereby support is afforded to said disks to prevent a rupturing strain thereon, an adjustable rod connected to the movable hub, and means, substantially as described, for controlling the flow of fluid through the reducer, as and for the purpose herein specified.

2. In a diaphragm, the combination of a resilient disk and a guard-plate secured together at the periphery, said guard-plate having a dishing form corresponding to said disk and lying within the bulging movement of the latter under pressure, whereby support is afforded to said disk to prevent a rupturing strain thereon, as and for the purpose herein specified.

ERNEST C. FASOLDT.
